UNITED STATES PATENT OFFICE.

OSCAR WILLIS, OF DIZARDVILLE, NORTH CAROLINA.

CENTRIFUGAL WATER-WHEEL.

Specification forming part of Letters Patent No. 12,569, dated March 20, 1855.

To all whom it may concern:

Be it known that I, OSCAR WILLIS, of Dizardville, in the county of McDowell and State of North Carolina, have invented certain new and useful Improvements in Water-Wheels; and I do hereby declare the following to be a full, clear, and exact description thereof, reference being had to the accompanying drawings, and to letters of reference marked thereon, in which—

Figure 1 represents a vertical transverse section through the center of the frame, flume, and wheel. Fig. 2 represents a broken view of the top and bottom of the block through which the water is let on the wheel. Fig. 3 represents a similar view of the wheel immediately underneath the block. Fig. 4 represents the form of block used in applying the water to the wheel from a high head. Fig. 5 represents a vertical section of the bucket, taken on the line of its motion.

The nature of my invention consists, first, in beveling the sides of the nut and rim of the wheel, which form the sides of the bucket, to such an extent as will give space for the water to pass off without offering any resistance to the pursuing bucket and at the same time to present a surface on each side of the bucket, diagonal to the central vertical line of motion, to receive the reactive power of the water acquired by its spreading on the bucket, and thus give additional speed to the wheel; second, in the peculiar set of the buckets at the top of the wheel, ranging on a line in front of the center of the wheel tangential to a circle of suitable diameter described around said center, so as to receive the water at such an angle as will overcome the centrifugal direction it has obtained in passing the inclined ways in the block or bottom of the forebay, and thus prevent it from running or rushing to the outer edge or rim of the wheel; third, in the rimming or shrouding of the wheel on top, so as to prevent the escape and loss of water in its application to the buckets, and to prevent injury being done to them by any hard substance hanging between them and the inclined ways in the block or bottom of the forebay; fourth, in so proportioning the orifice of discharge from the block to that at the tail of the bucket as that a column of water about one-third less in size than that of the orifice of discharge at the tail of the bucket is all that can be admitted at a

time to the wheel-buckets; and, fifth, in setting the buckets in the nut and rim of the wheel on a curved line, and bending the center part of the top edge of the bucket forward in the direction of its motion so that the top of the bucket is curved on its edge and the upper part of the central vertical section of the bucket where the water first strikes is a straight inclined plane at a slightly obtuse angle with the direction of the water.

In the construction of the wheel the nut or center part A, as well as the other parts of the wheel, may be of wood or iron or both combined, and will be of varying diameter with the quantity or head of water to be used or the speed required for the special machinery to be driven by it. A single wheel or two or more may be used on the same shaft. The rim B surrounds the nut A, and at such distance therefrom as will furnish the requisite space for the buckets C, which at top should never exceed two-thirds of the vertical measurement of the buckets, in order to get the best reactive effect from the smallest quantity of water, which will be hereinafter described. Said buckets are placed between the nut and rim and the whole firmly and substantially connected together to form the wheel. The rim B is beveled under on its inner side, as seen at a, Fig. 1. The nut is also beveled under, as seen at b, Fig. 1, so as to widen the space or water-way at the bottom of the wheel to about double the width of the orifice at the top of the wheel.

D represents the vertical shaft of the wheel, which is supported in suitable bearings in any well-known manner.

The buckets form a curved inclined plane in the direction of their length, and the heads or upper ends are curved in the direction of their width, or are bent forward at the center in the direction of their motion, so as to receive the water upon a straight inclined plane when it first strikes the bucket, and to prevent it from rushing to the sides by being curved in its width while exerting its percussive force upon it. The head of the bucket does not range toward the center of the wheel, but is on a line tangentially to a circle of suitable diameter described around said center.

The dotted line x, Fig. 3, represents the general direction of the head of the bucket, said line passing to that side of the center in

the direction of the motion of the wheel, so as to receive the water at such an angle as will counteract the centrifugal direction it has acquired in passing the inclined ways in the block or bottom of the forebay, and bring it to bear equally on the beveled sides of the nut and rim of the wheel. They are so curved longitudinally as that the bottom of the wheel, which is horizontal, forms a tangent with the tail or lower part of the bucket, so that in the passage of the water downward, after it has exhausted its power of percussion on the upper part of the bucket, it is, by its change of direction as it gradually approximates to an almost horizontal one, caused to spread and give out a reactive effect on the beveled or inclined sides of the bucket, formed by the beveling of the nut and rim, as well as a similar effect on the curved incline plane of the wheel-buckets by gravitation, which continues till the water leaves the wheel, by the gradual change of direction of the current.

The vertical longitudinal section of the bucket is curved, and to which the bottom of the wheel is tangential, as seen in Fig. 4. Its tail end is radial to the center of the wheel, as represented by the dotted line *y*, Fig. 3. The buckets are set so close together that the water may only strike on that portion of them at the top edge, which is a straight inclined plane at nearly a right angle with the inclines in the block above them. The upper part of the bucket (as well as the remainder of it) is set into the nut and rim on a curved line and afterward hammered back at the top edge in the direction of the wheel's motion, which makes the upper part of them straight on the incline down the center and at the same time curves the top edge, leaving it concave to the water. This has the effect of holding the water when it first strikes the bucket and preventing it from pressing laterally against the nut and rim at the upper part of the bucket, where, from the position of the sides, it could not exert any reactive influence in the direction of the wheel's motion, and as it passes from this concave part onto the transversely-flat part increases its tendency to spread against the diagonal sides of the lower part of the bucket in addition to such spreading or lateral flow, due to the change of direction of the current on the curved lower part of the bucket. If the buckets were placed wide apart, the water would strike low down upon the curve, and not only lose its second effect by leaving the wheel too rapidly, but would strike on a part of the curve whose angle of deflection from the direction of the water is not suitable to develop the percussive power of the water wholly in the direction of the wheel's motion. The top part of the bucket should be at a slightly obtuse angle from the plane of direction of the water in passing through the inclined ways in the block, so as to receive the water at an angle that will produce the greatest percussive effect and at the same time to incline it downwardly into the

curved part of the bucket, and being placed thus close together reserves about two-thirds at the lower part of the bucket to be operated on by the reaction of the water, as before described. The perpendicular distance of one bucket over the next is about two-thirds greater at the top than at the bottom, and their width is about double at the bottom than at the top. The head of the bucket *c*, Fig. 1, is not flush with the top of the wheel, but is from one to two inches below it, in proportion to the size of the wheel. That portion of the nut and rim above the head of the bucket, and which I term "shrouding" rises all around the water-space between the nut and rim and forms a beveled projection over the bucket, that portion on the rim projecting over them about half an inch, while that on the nut only projects over them about a quarter of an inch. This difference of projection of the shrouding over the buckets is also intended to lessen the lateral pressure of the water on the rim or outside support of the buckets, due to its centrifugal inclination, by introducing it on the wheel on a smaller circle than that of the buckets, and thus dividing its pressure equally on both nut and rim, while the shrouding itself protects the upper edge of the bucket from injury arising from any hard substance hanging between them and the inclined ways in the block above and at the same time prevents loss of water between the block or forebay and the wheel. I also use a similar shrouding *e* below or on the under side of the rim and nut to support and protect the tail of the bucket. A square block *E* sets over the wheel and may be hung or suspended by rods *f*, so as to be removable when it becomes necessary to repair the wheel below it. This block may be substantially made of timber or other suitable material and provided with a number of openings *F*, directly over the buckets of the wheel. The openings in the block *E* should contract about one-half from top to bottom—that is to say, when two inches wide at top they should be one inch at bottom, and are separated by sheet-metal divisions set at an angle of about forty-five degrees in the direction the wheel is intended to run. The passages thus formed in the block are for directing the water from the forebay onto the wheel's buckets. On the top of this block is a tub-formed water-guard *G*, for the purpose of keeping the water from the shaft of the wheel and throwing it toward the openings in the block. When the head of water is low, but abundant, the set of the buckets may be varied to a less curved form and the water discharged more directly down, even to an angle of thirty degrees, thus making the additional quantity of water supply the place of weight, in which case the form of block, &c., just described for introducing the water onto the buckets would be suitable; but if the head of water is much elevated, the water should be conducted to the wheel

through close pipes, terminating on opposite sides of the axis of the wheel in trunks H, Fig. 4, the under side of which are provided with openings having inclined division similar to those in the block already described for directing the water onto the wheel. Thus the water is confined in columns, the weight of which is made available, instead of the quantity, in which case the buckets should range at an angle of about forty-five degrees.

In applying these wheels to saw-mills or other machinery requiring the shaft to lie horizontally, two wheels should be placed on the same shaft, with their under sides or tails of the buckets toward each other, and the water applied through the blocks on the face of each wheel at the lower side; or they may be placed face to face on the same shaft and a block for introducing the water to each wheel supported between them.

I wish to be understood that I do not claim a curved bucket; nor do I claim beveling the nut and rim individually; nor do I claim them when combined in such a form as to facilitate the escape of the water only, as this has been done by Fontaine Jonval, and others previously; but,

Having thus described my invention, what I claim therein as new, and desire to secure by Letters Patent, is—

1. The peculiar double-curved buckets, in combination with the beveled rim and hub or nut, in the manner and for the purpose set forth.

2. Ranging the top of the bucket on a line tangential to a circle of suitable diameter described around the center, its inner side being in advance of the radial line, substantially as and for the purpose specified.

3. Shrouding the edges of the nut and rim at the top of the wheel around and within the annular water-space in such manner that the water is let onto the wheel in a smaller circle than that of the buckets—that is to say, the diameter of the annular space at the top of the shrouding being less than that at the tail of the bucket, each from center to center—as and for the purposes substantially herein described.

4. Forming the annular water-space on the upper side of the wheel, substantially as and for the purposes specified.

In testimony whereof I have hereunto subscribed my name this 29th day of July, 1854.

OSCAR WILLIS.
